CLAIM

The ornamental design for a cookware, as shown in described.

DESCRIPTION

FIG. 1 is an isometric view of the cookware showing the new design.

FIG. 2 is a top view thereof;

FIG. 3 is a bottom view thereof;

FIG. 4 is a right side view thereof;

FIG. 5 is a left side view thereof;

FIG. 6 is a front view thereof; and,

FIG. 7 is a rear view thereof.

The design is shown in solid lines in the drawings. The broken lines shown in the drawings depict portions of the cookware that form no part of the claimed design.

1 Claim, 4 Drawing Sheets---
